UNITED STATES PATENT OFFICE.

LAWRENCE T. THORN, OF LYNNVILLE, TENNESSEE.

RAILROAD-TIE.

1,133,761.

Specification of Letters Patent.

Patented Mar. 30, 1915.

Application filed August 7, 1914. Serial No. 855,675.

To all whom it may concern:

Be it known that I, LAWRENCE T. THORN, a citizen of the United States, residing at Lynnville, in the county of Giles and State 5 of Tennessee, have invented certain new and useful Improvements in Railroad-Ties; and I do hereby declare the following to be a full, clear, and exact description of the invention, such as will enable others skilled in 10 the art to which it appertains to make and use the same.

This invention relates to new and useful improvements in railroad ties and has for its principal object to provide a tie which 15 will effectively hold the rails in place and prevent them from sinking or creeping.

Another object of the invention is to provide a device that will eliminate the usual tie plate and substitute in lieu thereof a 20 plate extending throughout the entire length of the tie and carrying fastening means.

Another object of the invention is to provide a simple and effective means to prevent 25 the railroad rail from spreading and thus endangering the traffic passing thereover.

With these and other objects in view the invention consists in the combination and arrangement of parts which will be fully set 30 forth in the following specification and in the accompanying drawings, in which,

Figure 1 is a side view in elevation of a tie constructed in accordance with this invention illustrating the same as it would appear with the rails in place, Fig. 2 is a top plan view of Fig. 1, Fig. 3 is a longitudinal sectional view through the center of Fig. 2 illustrating in detail the rail securing means, Fig. 4 is an enlarged detail perspective view 40 of one of the rail clamp locking elements, Fig. 5 is a side view in elevation of a modified form of rail securing plate, Fig. 6 is a top plan view thereof, Fig. 7 is a detail sectional view taken on line 7-7 of Fig. 1, Fig. 8 is an enlarged detail perspective view 45 of one of the rail clamps, and Fig. 9 is an enlarged detail perspective view of the cooperating rail clamp used in connection with a modified form of the invention.

Referring now to the drawings by characters of reference, the numeral 1 designates a wooden tie of the usual construction to which the tie plate 2 is secured. This tie plate is formed near each end with the dove-tail groove 3 the inner end of which terminates in the enlarged recess 4. Slidable in

the dove-tail groove and arranged to be removed through the recess 4 is the rail clamping member designated generally by the numeral 5 which comprises the base portion 60 6 having the angularly extending wall 7 which is arranged to conform to the shape of the dove-tail groove and this base member 6 is provided with the upwardly inclined rail flange engaging member 8 which is arranged to engage the upper side of the rail flange and hold the railroad rail in place. A similar rail clamp is arranged to cooperate with the one previously described and this rail clamp is arranged to fit the inside 70 of the rail and it will thus be seen that a simple and effective means is provided for securing the rails to the tie. The rail clamps are preferably of sufficient length to come within a short distance of the end of 75 the dove-tail portion of the recess and the remaining portion is filled with the rail clamp securing element which will be more fully hereinafter described.

The rail clamp securing element previously mentioned, is best illustrated in Fig. 4 and comprises the plate 9 having formed near one end the aperture 10. This plate is provided at its opposite end with the dove-tail extension 11 and this extension is of sufficient length to fill the remaining space between the terminal of the dove-tail portion of said groove between the recess and the rail clamp.

In order to hold the rail locking member 90 in place, there is provided a suitable bolt 12 which extends into a threaded aperture formed in the bottom wall of the recess and it will thus be seen that when the bolt 12 is tightened the plate will be firmly held 95 against accidental movement and thus lock the whole together.

In the modified form of the invention, the tie structure is essentially the same excepting that the body 2 is supported on a pair 100 of spaced flanges and the rail locking plate is formed with a rail clamp at the end opposite to the dove-tail extension. This structure is best illustrated in Fig. 9 and it will be apparent that when the same is in place 105 a rail may be supported centrally of the tie and will be rigidly held thereto, thereby providing means for supporting three rails on the tie.

It is to be understood that in order to provide for clamping rails of different characters, the filler members designated by the

5 numeral 13 are provided and are arranged to be inserted between the outer rail clamp and the outer end wall of the slot in which the device is used. Thereby upon removing 10 or inserting the filler members it will be evident that rails of varying sizes may be firmly held in place on the tie, and accidental movement thereof will be eliminated.

15 It will be apparent from the foregoing that in use the ties are laid in the usual way and the outside rail clamp placed in position in the dove-tail groove. The rail is then slipped in place beneath the flange engaging portion 8 of the tie clamp and the co-operating tie clamp is then placed in the dove-tail groove and slid into engagement with the rail. The rail clamp securing means is then placed in the recess 4 and the dove-tail extensions thereon slipped into the dove-tail 20 groove and against the inner rail clamp and the device is then pressed downwardly so that the upper face thereof alines with the upper face of the tie and lies flush therewith. The bolt 12 is then put in position 25 through the aperture 10 formed in the clamp locking means.

30 It will be clearly seen that a simple and efficient method of securing the rails to the tie is provided.

35 30 While in the foregoing there has been shown and described the preferred embodiment of this invention it is to be understood that such changes in the combination and arrangement of parts as may fall within the scope of the claims may be resorted to without departing from the spirit and scope of the invention.

What is claimed is:—

40 1. A railroad tie including a body, said body being provided with a dove-tail groove near each end, recesses communicating with the grooves, the bottom wall of the recess being provided with a screw-threaded aperture, rail clamps slidable in the dove-tail

45 grooves, said rail clamps conforming to the shape thereof to prevent the same from being accidentally removed and a clamp locking plate removably held in the recess and arranged to abut the rail clamp to prevent the same from becoming accidentally removed. 50

2. A railroad tie including a body, said body being provided with a dove-tail groove in its upper face, a pair of rail clamps slideable in the dove-tail groove, the body also being provided with a recess in its upper face, said recess communicating with the dove-tail groove, the rail clamps being only of sufficient size to partially fill the dove-tail groove, a plate arranged to be inserted in the recess to fill the same and a dove-tail 55 extension on the plate, said dove-tail extension being arranged to engage the rail clamps to hold the same firmly in place.

3. A railroad tie including a body, said body being provided with a dove-tail groove 60 in its upper surface, said groove extending longitudinally of the tie, a recess formed in the tie adjacent the groove and arranged to communicate therewith, said recess being of the same width as the width of the widest 65 part of the groove, rail clamps slideable in the groove, said rail clamps being of sufficient length to nearly fill the entire groove, a plate arranged to fit the recess, means to hold the plate in the recess to prevent the 70 same from becoming accidentally removed and a dove-tail extension on one end of the plate, said dove-tail extension being arranged to engage the rail clamps and fill the 75 space between the rail clamps in the end of the dove-tail groove to hold the rail clamps against movement.

In testimony whereof I affix my signature in presence of two witnesses.

LAWRENCE T. THORN.
